FIG. 1

FIG. 2

Inventor

Chester C. Huffman

By

A. F. Flounoy Attorney

UNITED STATES PATENT OFFICE

133,130

DESIGN FOR A BADGE OR SIMILAR ARTICLE

Chester C. Huffman, Shreveport, La.

Application April 6, 1942, Serial No. 106,475

Term of patent 7 years

To all whom it may concern:

Be it known that I, Chester C. Huffman, a citizen of the United States, residing at Shreveport, in the parish of Caddo and State of Louisiana, have invented a new, original, and ornamental Design for a Badge or Similar Article, of which the following is a specification, reference being had to the accompanying drawing, forming part thereof.

I claim:

The ornamental design for a badge or similar article, as shown.

CHESTER C. HUFFMAN.
